RHEOSTAT

Newton C. Schellenger, Elkhart, Ind., assignor to
Chicago Telephone Supply Company, a corpora-
tion of Indiana

Application May 26, 1933, Serial No. 672,955

12 Claims. (Cl. 201—55)

My invention relates to an electrical circuit control device and relates more particularly to a rheostat as commonly used in radio circuits.

In my copending application, filed December 7, 5
1931, Serial No. 579,552, issued as Patent No. 1,920,217, Aug. 1, 1933, and of which this is a continuation in part, I have shown a variable resistance unit or rheostat, commonly known as a volume control, combined with a switch; both the 10 switch and rheostat being actuated from the same operating shaft.

It is an object of my invention to employ a spring arm of very light material, which engages the contact shoe of the resistance element.

15 A further object of my invention is to embody an inconspicuous, serviceable device whereby a violent jolt of the unit will not dislodge the contact shoe from the pressure arm.

A further object of my invention is to construct 20 the terminal members so that an inadvertent bending or displacement of the low resistance terminal member will cause no change in the low resistance hop-off.

Other objects of this invention are to provide 25 an improved device of the character described, that is easily and economically produced, which is sturdy in construction and which has a maximum of efficiency and accuracy.

With the above and related objects in view, my 30 invention consists in the following details of construction and combination of parts, as will be more fully understood from the following specification, taken in conjunction with the drawings, in which:—

35 Figure 1 shows a fragmentary sectional view of my invention embodied in a rheostat and combined with a snap switch;

Figure 2 is a plan view of the resistance element and terminals;

40 Figure 3 is a perspective view of the contactor arm, its support and shaft;

Figure 4 is a rear view of the contactor arm support, showing the unsymmetrical placing of the holding rivets;

45 Figure 5 is a fragmentary side elevational view showing the swedging out of the shaft holding means at the end of the bushing;

Figure 6 is a sectional view taken on the line 50 6—6 of Figure 5;

Figure 7 is a plan view of the washer biting into the insulating plate;

Figure 8 is a fragmentary side elevational view of Figure 7, more clearly showing the burr on the 55 edge of the slots of the washer;

Figure 9 is a fragmentary side elevational view showing the attachment of a terminal;

Figure 10 is a fragmentary plan view of the terminal;

Figure 11 is a plan view of a modified contactor 5 arm and contacting shoe;

Figure 12 is a front view of the shoe and contactor arm shown in Figure 11;

Figure 13 is a fragmentary sectional view of a tandem arranged rheostat embodying my invention;

Figure 14 is a plan view of another type of pressure arm wherein the arms are supported in a manner to prevent twisting;

Figure 15 is a modification of the arm as disclosed in Figure 14;

Figure 16 is a plan view of a tandem arranged pressure arm;

Figure 17 is the opposite face of Figure 16;

Figure 18 is a cross-sectional view taken on the 20 line 18—18 of Figure 14; and

Figure 19 is a cross-sectional view taken on the line 19—19 of Figure 15.

Figure 20 is a plan view of the rheostat shown in Fig. 1. 25

Figure 21 is a plan view of my rheostat, showing a cover grounding plate and positioning lugs.

Figure 22 is a broken sectional view of the rheostat shown in Figure 1.

Referring now to the drawings in more detail, particularly to Figs. 1, 2 and 3, it will be seen that the instrumentalities of the rheostat are mounted upon a base or mounting disc 10 which may conveniently be formed of an insulating material such as phenol condensation product commonly known as "bakelite".

The resistance element 12, preferably a carbonaceous coated strip of generally arcuate shape, is placed upon one of the flat faces of the base or mounting disc 10, and is held thereagainst by terminal members 14 and 16 engaging its ends. 35

As will be seen in Figs. 2, 9 and 10, the terminal member 16, of a single strip of conducting material of uniform thickness, has a foot 18 disposed in engagement with one end of the resistance element 12 and is pierced for the reception of an attaching means, shown for convenience as an eyelet 20. The foot portion 18 of the terminal contains an arcuate recess 22 so that the length 45 of the terminal edge in close proximity to the shoe, when the shoe is adjacent the terminal, will be greater than if the terminal had a straight edge extending across the resistance element, and as a consequence the minimum resistance between 50

55

the shoe and the terminal is lower than would otherwise be obtained.

The terminal member 14, at the low resistance end of the resistance element, may have a diverging extension 24 from the foot member 26, as shown in the terminal 14 of Fig. 2, to engage an edge of the resistance element to provide for a slow resistance increase upon the arcuate movement of a contact shoe 28. In this manner, virtually any desired initial resistance gradient may be obtained.

A similar arrangement may be embodied at the high resistance terminal, and the only thing necessary will be to make the high resistance terminal complementary to the low resistance terminal, that is, one of the members is a right hand member and the other a left hand member.

The diverging extension 24 also functions to keep a low initial resistance in the circuit until 20 the switch, mounted on the cover, is closed.

The neck 30 of the terminal 16 is bent sharply adjacent the foot portion 18 and is fitted in a slot 32 in the periphery of the mounting plate 10 to prevent the terminal member from being turned 25 circumferentially with respect to this plate. The neck is then turned back upon itself and tapers in width, as indicated at 34. The terminal extends at an angle to the plane of the cylindrical casing face to permit the easy attachment 30 of the various lead wires. To prevent the displacement of the foot portion of the terminals 14 and 16 with a consequent increase in the minimum resistance, should there be an axial bending 35 of the terminals, narrow sections 15 and 17 respectively have been provided in the lug portion of the terminals so that bending will first take place at these points and no harm result.

Bushing

40 Mounted concentrically in the disc 10 is a suitable journal bushing or thimble, generally designated as A, which may also serve as a panel mounting device for the unit. This bushing A may be threaded exteriorly as at 36 for the reception 45 of a nut by which the assembly is clamped upon a suitable panel or bracket, that is, by the usual and well known type of mounting, and the bushing also has a central longitudinal opening 38 therethrough.

50 The bushing A contains an annular flange 40 disposed against the surface of the disc 10 upon which the resistance element 12 is located, and if desired, this flange 40 may be serrated on one face as shown at 42 so that it will bite into the 55 disc 10 and lock that disc against rotation with respect to the bushing.

A shoulder or swaging portion 43, of smaller diameter than the flange and emerging from the flange, protrudes through the base opening 44 60 and also through a central opening in a holding clamp B, and the end of the shoulder 43 is swelled 65 to grip the face of the clamp and to engage a plurality of spaced niches 46 (Fig. 20) in the clamp B for the prevention of rotary motion of the disc and the holding clamp B in a direction about the axis of the shaft, and in a direction along the shaft. If further rotational restraint is desired, burrs are provided along the radial edges of the niches 46, so that they engage the 70 disc 10 when the shoulder 43 of bushing A is swaged in place. This very definitely locks the disc 10 and clamp B together and may be used instead of the knurling 42 on the flange 40. Protruding lugs 39 on the clamp B are adapted to co- 75 operate with holes in the panel, upon which the

rheostat is to be mounted, and prevent rotation of the rheostat relative to the panel.

Contactor arm

An operating shaft, generally designated C, and journaled in the thimble A, is comprised of a cylindrical portion 48 of suitable length and a reduced substantially rectangular end 50, see Figs. 3 and 4. A thin insulating plate D substantially of circular formation, has a plurality 10 of extending ears 52 and 54 on the periphery adapted to engage a suitable stop member 56 protruding from the stud 114 for limiting the rotation of the arm in either direction, and the plate, also, has a central elongated opening 58 to fit onto the end 50 of the shaft. The insulating plate is placed upon the reduced end 50 of the shaft 48 and a washer, generally designated E, having a central opening to also fit onto the reduced end 50 of the shaft is placed thereon and the face of the reduced end is then swaged over, holding the shaft C, the plate D and the washer E in position. The washer has, see Figs. 7 and 8, a plurality 15 of radial slots or notches 60 and 62 with burrs 61, 63, 64 and 65 along the radial edges of the notches, 25 which burrs are adapted to bite into the insulating plate, thus preventing relative rotation of the shaft and insulating plate.

A resilient contactor or pressure arm F, preferably of a single piece of suitable thin conducting material and supported by the plate D, is comprised of an arcuate shaped cantilever arm 66 supported at each end by integral formed yoke portions 68 and 70, which yoke portions in turn are united to a central slip-ring section 72 having an internal diameter substantially larger than the diameter of the shaft 48, as shown in Figure 3, to space the slip ring section from the shaft in an insulating relationship thereto. The contactor arm is also provided with a peripheral 40 cutout portion 74, which is adapted to fit about an eccentrically mounted operating pin 76 carried by the insulating plate D. The arcuate shaped arm has verging from its unsupported mid-portion a projecting tip or boss 78 adapted 45 to engage the perforated disc or shoe 28, which engages the resistance element. However, the tip may be constructed to actually engage the resistance element, or may take a variety of forms as shown in Figs. 11 and 12, as hereinafter more 50 fully described.

A modified pressure arm G, Figs. 11 and 12, has a short conical boss 80 and two projecting lugs 82 and 84.

A flat contact shoe 85 has two diametrically opposed holes 86 and 88 therein, which receive the projecting lugs 82 and 84, respectively, of the pressure arm. The pressure exerted by the arm G is directed against the central portion of the shoe 85 by the conical boss 80 engaging the upper 60 surface of the contact shoe.

The contact shoe is drawn along the resistance element by one or the other lug of the pressure arm engaging the edge of one of the holes in the shoe 85, so that the shoe is always pulled along 65 the resistance element.

The contactor or pressure arm F is mounted upon the insulating plate by means of suitable eyelets or rivets 90 and 92, see Figs. 3, 16 and 17, which eyelets or rivets are unsymmetrically 70 placed, as will be hereinafter further described. The arm F is so mounted that the tip 78 will be approximately equi-spaced from the extending ears 52 and 54, Fig. 17.

Now referring again to my preferred embodiment 75

ment shown in Fig. 3, the stamped-out arm F has an aperture 94 near the rivet 92 to provide clearance around a rivet or bolt 91 (Fig. 17), when a second arm H (Fig. 16) is inserted on the opposite 5 face for a tandem arranged series of rheostats.

Pressed out projections 96 and 98 to each side of the free end of the cantilever arm and extending in a direction opposite to that of the tip 78 are adapted to engage one face of the insulating 10 disc to prevent the contacting shoe from separating from the lug 78.

Considerable difficulty is experienced when manufacturing rheostats, in securing a uniform predetermined pressure between the contacting 15 shoe and the resistance element, and between the spring member K and the contact arm F, both of which are very necessary if low resistance contacts and long life are to be expected. Predetermined pressures are obtained with my rheostat 20 by assembling the parts in proper axial alignment and then applying the desired pressure to the shaft C in an axial direction and in such a manner that it is resisted by the pressure between the contacting shoe and resistance element 25 plus the pressure between the arm F and spring member K. These pressures are maintained by swaging the shaft, when in the desired position (Figs. 1, 5 and 6), at 101, so that it is enlarged at this point and forms a shoulder 30 that bears against the washer 100, which is in contact with one end of the thimble A.

It is particularly to be noted that with this method of assembly, no unnecessary strain whatsoever is placed upon the contactor or resilient 35 arm by pressing the contact shoe 28 in engagement with the resistance element during the swaging action.

Slip-ring and washer

40 Disposed upon the surface 102 of the thimble A is an insulating washer J, Figs. 1 and 2, having diametrically placed peripheral notches 104 and 106 therein.

45 A ring-shaped slip-ring member, generally designated K, and having a concave face 108 adjacent the insulating washer J, has a short lug 110 and a long lug 112, Figs. 1, 2 and 13, extending from the periphery of the face 108. The lugs 110 and 112, when suitably bent, extend or fit 50 into the notches 104 and 106 of the insulating washer, and the long lug is also adapted to provide the electrical take-off for the derived electrical circuit. The stud 114 serves to connect the long lug 112 of the slip-ring member to a 55 terminal 116 and secures the slip-ring and terminal in electrical relationship. It is to be particularly noted, see Fig. 1, that the slip-ring K is axially resilient to provide a good electrical contact with the movable slip-ring 72.

60 Both the washer J and the slip-ring member K are provided with central aligned openings for receiving the control or operating shaft C, the apertures formed in the slip-ring member K being of a larger diameter than the opening or aperture through the washer J, so the slip-ring member K will be spaced from the control shaft and thus insulated therefrom.

Tandem

70 Heretofore, the tandem or double type of rheostat construction, in which the pressure arms were insulated from each other (shown in Fig. 13), required a large casing, but by my novel unsymmetrically arranged contact arm F supported upon the insulating base D (shown in Figs.

16 and 17) by eyelets 90 and 92, I economize in space by placing an additional contact arm H, similar in structure to the arm E, (but one arm being so-called "right-handed" and the other "left-handed") upon the vacant face 118 of the 5 insulating strip and securing it in place with eyelets 94 and 93. It will be noted that there is no electrical connection between the two arms, as each arm is cut out both to clear the eyelets that hold the arm in place, and to clear the shaft. I 10 have thus provided an insulated pressure arm for the second rheostat section without the addition of another shaft, bushing, or mounting plate, such as has been used in the past. The second 15 rheostat section is comprised of a second insulating base 120, held in the housing 140 by the eyelet 141, and positioned angularly by formed in sections in the housing co-operating with notches in the periphery of the base 120. A resistance element 143 is carried by the base 120 20 and is contacted by a shoe 144 driven by the pressure arm H. Terminals for the resistance element and for the spring connector K, which contacts the arm H, are provided and extend through notches in the base 120 and through 25 an opening in the metal housing 140 that is sufficiently large to provide good insulation.

Switch operation

In order to provide for the operation of a 30 switch or circuit controller, the insulating disc D may be provided with an eccentrically mounted pin 76.

This pin 76 projects normal to the plane of 35 the insulating disc and is located to engage an operating arm or ear 122 of the switch mechanism S. A movement of the insulating disc D will, therefore, operate the switch mechanism. The switch S, shown by way of example, may be any preferred type of switch suitable for 40 this purpose, such as the switch shown in my copending application, Serial No. 602,006, filed March 30, 1932, to which application reference is now made for the details of the construction 45 of the switch and the manner of mechanical arrangement.

Mounting

The casing 11, within which the rheostat is housed, is provided with a plurality of projecting 50 ears 150, which are registered in peripheral slots 124, 126, 128 and 130 on the base and bent over to attach the casing to the plate. The registration of the ears with their respective slots 124, 126, 128 and 130, accurately aligns and holds the 55 housing with respect to the plate both in a rotary direction about the axis of the shaft and in a direction along the shaft. By this means, the alignment of the rheostat and switch may be predetermined so that the two will function cooperatively. 60

The casing or housing for the rheostat, which also supports the switch, may be attached to the base by any suitable means, but preferably by the means as disclosed in either of my copending 65 applications, Serial No. 668,757, filed May 1, 1933, or Serial No. 671,031, filed May 15, 1933.

It is in many cases advantageous to provide 70 a rheostat enclosed almost entirely in metal, so that all of the operating parts are electrostatically shielded from outside electrical disturbances. This is especially true when a switch is mounted on the cover and is to be used for switching a fluctuating current. I have found 75 it possible to very efficiently and economically

accomplish both of the above results with the plate L (Figs. 21 and 22) from which the lugs 239 are formed. Plate L is mounted over the base 10 so that the insulating base is almost completely shielded. This plate L is also in electrical contact with the mounting bushing or thimble A, which will normally be mounted on a grounded metal panel, and has clinched over onto it the ears 150 of the cover member 11. It is therefore necessary to ground only the thimble to accomplish the necessary electrostatic shielding of the rheostat from the switch and other external disturbances. In many instances, it is possible to effect economies in the manufacture of radio sets by extending the grounding plate to one of the terminals of the resistance element.

In Fig. 21, I have shown plate L carrying a terminal 14, which replaces one of the regular terminals. This terminal is normally connected to ground by virtue of being a part of the plate L, which is normally grounded. It is also connected to one end of the resistance element (the end that is desired to be grounded) by the eyelet 201 and a washer or plate on the inside of the rheostat bearing against the element and held in place by the eyelet. When a grounded terminal is not desired, the plate L is made according to the dotted lines 270.

Two ears 239 integral with the plate L and formed at right angles to it are adapted to register with holes in the mounting panel to prevent rotation of the control relative to the panel during assembly and afterward. A washer or spacer 276 is assembled on the thimble A, preferably in a permanent manner, to provide an even substantial mounting surface and to space the terminals and ears away from the panel.

Referring now to Figs. 14 and 18, I show a pressure arm of the same general type as, but having certain valuable improvements over, the arm covered in my Patent No. 1,913,686 of June 13, 1933. With the arm of my prior patent, there was a tendency for the two converging sections to twist when a pressure was applied against the contact paddle, due to the bowing of the yoke section caused by the pressure on the ends of the yoke being in a reverse direction to that on the contact projection. This twisting seriously impaired the flexibility of the arm as a whole, since the legs were free to bend in the desired direction for only a small part of their total length, the balance of their length being twisted and not free to bend.

This is overcome in the arm disclosed in Figs. 14 and 18 by strengthening the yoke carrying the lug 212 by a rib or offset portion 210, and by strengthening the rear section with a rib or offset portion 214. By strengthening the front and rear yoke portions in this manner, twisting of sections 204 and 206 is prevented, and a good distribution of flexing obtained.

I have accomplished this same end in the arm shown in Figs. 15 and 19 by securing the ends of portions 250 and 252 to the plate 254, which is quite rigid, by eyelets 256 and by strengthening the front yoke portion by bending a portion 262 at a substantial angle to the main part of the yoke 258.

Although the invention has been described in considerable detail, such description is intended as illustrative rather than limiting, as the invention may be variously embodied, and the scope of the invention is to be determined as claimed.

75 I claim as my invention:

1. A variable resistance device comprising, a mounting thimble, a serrated enlarged head on said thimble, a shoulder of lesser diameter and emerging from said head, an insulating base having the serrations engaging one face of said base, a mounting washer having an irregular opening therein and engaging the opposite face of said base, said shoulder of the thimble being expanded to hold the thimble, base and mounting washer together. 10

2. A tandem unit variable resistance device comprising a pair of spaced opposed bases, a resistance element on each of said bases, a rotatable shaft extending through at least one of said bases, an insulating plate carried by said shaft between said bases, contact arms mounted respectively on each side of said plate, contact shoes engaged by said contact arms respectively and bearing against the corresponding resistance elements, and oppositely disposed resilient means arranged on each side of said plate and bearing on each of said contact arms to establish electrical connection therewith. 15 20

3. A tandem unit variable resistance device comprising a housing having a pair of spaced substantially parallel end walls, a flat resistance element on the inside face of each of said end walls, a rotatable shaft extending through at least one of said end walls, a flat plate carried on said shaft 30 and disposed between and substantially parallel to said end walls, a resilient contact arm on each side of said plate respectively, means securing said arms respectively to said plate at an end of each arm, a contact shoe bearing upon each resistance 35 element respectively and engaged respectively by the free ends of said resilient arms, and a pair of spring tensioned collector brushes, each disposed on opposite sides of said plate in electrical engagement with each of said contact arms, respectively, said brushes being disposed to exert axial thrusts on said shaft through said plate, the thrust of either of said brushes off-setting the thrust of the other thereof. 40

4. A tandem unit variable resistance device comprising a housing having a pair of spaced opposed end walls, a resistance element on the inner face of each end wall respectively, a rotatable shaft extending through at least one of said end walls, a flat insulating plate disposed between said end walls and carried on said shaft, a resilient contact arm on each side of said plate respectively, means securing an end of each contact arm respectively to said plate, a contact shoe bearing against each of said resistance elements respectively and engaged by the free ends of the corresponding contact arm and a resilient current collecting member interposed respectively between said plate and said end walls respectively to resiliently position said plate in said housing. 55 60

5. A variable resistance device comprising a base, a resistance element on said base, a terminal having an arcuately recessed portion overlying and contacting the surface of said resistance element, a disk-like contactor engaging and movable over the surface of said resistance element and shaped to nest in the recessed portion of said terminal, and means engaging said contactor for moving the same over said resistance element and into the recess in said terminal wherein said shoe 70 lies substantially concentrically when nested in said recess.

6. The combination with a switch, of a variable resistance device comprising a housing carrying said switch, a resistance element in said housing, 75

a terminal engaging said resistance element adjacent one end, a contactor movable over the surface of the resistance element, means including an arm for moving said contactor, means on said 5 arm for operating said switch during the movement of said contactor over a portion of said resistance element adjacent said terminal, said terminal having an arm extending along a margin of that portion of the resistance element traversed 10 by the contactor during that portion of its travel wherein said switch is operated.

7. The combination with a switch, of a variable resistance device comprising a housing carrying said switch, a resistance element in said housing, a 15 contactor movable over the surface of said resistance element, a terminal engaging said resistance element adjacent one end and having an elongated leg extending in the direction of and adjacent the path of said contactor, means including 20 an arm for moving said contactor, and means including an element carried by said arm for actuating said switch during the movement of said contactor along that portion of its path adjacent said elongated leg.

8. In a variable resistor, a base member, a shaft 25 journalled in said base member, a contactor secured to said shaft for movement therewith, a slip ring carried by said contactor, a spring collector ring spaced from and concentric with said shaft disposed between said contactor and base member, said collector ring being tensioned to exert an axial thrust on said shaft through said contactor, and an elongated appendage extending 30 from said collector ring adapted to connect said contactor to an outside circuit.

9. In a variable resistor, a housing, a threaded mounting thimble centrally disposed in one wall of said housing, a shaft journalled in said thimble, a contactor secured to said shaft for movement 35 therewith, a spring collector ring positioned upon said thimble in engagement with said contactor, a

tail member extending from said collector ring, said tail member being fastened to maintain said collector ring in spaced, concentric relation to said shaft, and an insulative member interposed between said thimble and said collector ring. 5

10. In a variable resistor, a base member, a bushing carried by said base member, a shaft journalled in said bushing, a contactor mounted on said shaft for rotation therewith, an insulative disc disposed to overlie said bushing, a resilient metal brush disposed about said shaft tensioned 10 between said contactor and said insulative disc and having a bearing on each of them.

11. In a variable resistor, a base member, a bushing carried by said base member, a shaft 15 journalled in said bushing, a contactor mounted on said shaft for rotation therewith, an insulative disc disposed to overlie said bushing, a resilient metal brush disposed about said shaft tensioned 20 between said contactor and said insulative disc 25 and having a bearing on each of them, cooperating means between said insulative disc and brush member for holding said brush immovable relative to said base member whereby the insulative disc holds the brush spaced from contact with the shaft.

12. In a variable resistor, a base, a bushing mounted in said base, a shaft journalled in said bushing, a contactor mounted on said shaft for rotation therewith, an insulative disc disposed 30 upon said bushing, a resilient metal brush compressed between said contactor and said insulative disc, a conductive tail extending from said brush, said tail being secured to said base for making 35 connection to an outside circuit, and positioning means for said brush comprising portions on said disc, brush and tail cooperating to fixedly mount said brush relative to said base spaced from contact with the shaft.
